UNITED STATES PATENT OFFICE

SEYMOUR TROY, OF BROOKLYN, NEW YORK

DESIGN FOR A WOMAN'S SHOE

Application filed September 19, 1930. Serial No. 37,017. Term of patent 14 years.

To all whom it may concern:

Be it known that I, SEYMOUR TROY, a citizen of the Republic of Poland, residing at Brooklyn, county of Kings, State of New York, have invented a new, original, and ornamental Design for a Woman's Shoe, of which the following is a specification, reference being had to the accompanying drawing, forming a part thereof.

Fig. 1 is a side view of a woman's shoe showing my new design.

Fig. 2 is a rear view of a woman's shoe showing the rear portion of my new design.

The diagonal hatching, shown in the drawing, represents gold cloth and the vertical-horizonal hatching represents silver cloth.

I claim:

The ornamental design for a woman's shoe substantially as shown and described.

SEYMOUR TROY.
